(57) **CLAIM**

The ornamental design for a controller and display, as shown and described.

DESCRIPTION

The design is for a control and display unit for use in an electronic propane fuel tank monitoring system or the like. FIG. 1 is a back, elevation view of the controller and display, showing an embodiment of the design of this invention.

FIG. 2 is a top view thereof.

FIG. 3 is a front view thereof.

FIG. 4 is a bottom view thereof.

FIG. 5 is a end view thereof.

FIG. 6 is an opposite end view thereof.

FIG. 7 is a perspective view thereof; and,

FIG. 8 is another perspective view thereof.
